US0D1078398S

(12) **United States Design Patent** (10) **Patent No.:** **US D1,078,398 S**
(45) **Date of Patent:** **** Jun. 10, 2025**

(54) **THERMAL CONTAINER**

(71) Applicant: **Xiaolei Chen**, Hefei (CN)

(72) Inventors: **Xiaolei Chen**, Hefei (CN); **Kent Yiyu Shi**, Hefei (CN)

(**) Term: **15 Years**

(21) Appl. No.: **29/990,758**

(22) Filed: **Feb. 24, 2025**

(30) **Foreign Application Priority Data**

Feb. 5, 2025 (CN) 202530054066.8

(51) **LOC (15) Cl.** **07-10**

(52) **U.S. Cl.**

USPC **D7/608**

(58) **Field of Classification Search**

USPC ..... D7/323, 354, 355, 387, 388, 601, 602, D7/605, 608, 619.1, 620, 624.1, 624.2, D7/629, 402, 409, 412, 538, 540, 542; D9/414, 428, 430, 431, 432, 434, 499, D9/738; D3/202, 229; D12/419, 415 CPC A47B 55/00; A47B 55/02; A47B 73/002; A47G 19/30; A47G 21/00; A47J 36/34; A47J 37/0694; B65D 7/20; B65D 21/00; B65D 21/02; B65D 21/0233; B65D 2453/00296; B65D 81/00; B65D 81/18; B65D 81/34; B65D 81/3453; B65D 81/3813; B65D 81/3876; B65D 2581/34; B65D 2581/3437; F24C 15/16

(57) **CLAIM**

The ornamental design for a thermal container, as shown and described.

DESCRIPTION

FIG. 1 is a top, front, and right side perspective view of the thermal container, showing our new design;

FIG. 2 is a bottom, rear, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the thermal container that form no part of the claimed design.

1 Claim, 8 Drawing Sheets
